UNITED STATES PATENT OFFICE

137,737

DESIGN FOR A HANDWHEEL FOR VALVES AND THE LIKE

Gates F. Parkin and Leslie A. Brown, Meriden, Conn., assignors to International Silver Company, Meriden, Conn., a corporation of New Jersey

Application September 18, 1943, Serial No. 111,158

Term of patent 14 years

(Cl. D78—1)

To all whom it may concern:

Be it known that we, Gates F. Parkin and Leslie A. Brown, citizens of the United States, residing at 221 Williams Street, Meriden, county of New Haven, State of Connecticut, and 183 Britannia Street, Meriden, county of New Haven, State of Connecticut, respectively, have invented a new, original, and ornamental Design for a Handwheel for Valves and the Like, of which the following is a specification, reference being had to the accompanying drawing, forming part thereof.

Fig. 1 is a front view of a hand wheel for valves and the like showing our new design; Fig. 2 is a back view thereof; and Fig. 3 is a side view thereof.

We claim:

The ornamental design for a handwheel for valves and the like, as shown.

GATES F. PARKIN.
LESLIE A. BROWN.
